UNITED STATES PATENT OFFICE.

FREDERICK MANKEY, OF WILLIAMSPORT, PENNSYLVANIA.

PROCESS OF MAKING OPEN-WORK ORNAMENTAL PANELS.

SPECIFICATION forming part of Letters Patent No. 351,060, dated October 19, 1886.

Application filed August 25, 1885. Serial No. 175,225. (No model.)

To all whom it may concern:

Be it known that I, FREDERICK MANKEY, of Williamsport, Lycoming county, Pennsylvania, have invented a certain new and useful 5 Improvement in Processes of Making Open-Work Ornamental Panels, of which the following is a specification.

My invention consists in a new method of producing open-work or reticulated panels 10 from wood or other suitable material, the process being simpler and cheaper than any now in use.

In the accompanying drawings, Figure 1 is a plan view of a board which has been subjected to the first steps of my process. Fig. 2 represents an edge view of said board, and also a side view of a strip cut therefrom in the second step of said process. Fig. 3 is a top view of said strip. Figs. 4 and 5 represent, respectively, side and top views of said strip after it has been subjected to a third step, which I consider desirable, though not essential, in said process; and Fig. 6 represents the 25 open-work or reticulated panel finally formed, Fig. 7 being a section thereof on the line $x-x$ of Fig. 6.

I carry my new process into effect in the following manner: A suitable piece of timber being selected, I subject it to the action of a rotary cutter or series of cutters, whereby the 30 surface of the material is cut transversely to the grain in channels and ridges. Thus, to form the particular design represented in the drawings the wood is cut transversely with channels A and intermediate ridges, B, having convex sides, as shown in Fig. 1. The plank or board, having been cut in this way on both sides, is afterward divided longitudinally with the grain or in a direction at right 35 angles to said channels, as indicated by dotted lines, Fig. 1, thus producing a number of strips, G, similar to those shown in Figs. 2 and 3, the tops of the ridges now appearing as projections b upon each side of a flat strip, and the sides of the channels A now appearing as 40 curved V-shaped depressions a between said projections. To produce a highly-ornamental surface in the finished panel, I then prefer to pass the strips shown in Figs. 2 and 3 through

a molding-machine, for example, whereby they 50 are beveled along both edges and indented or transversely channeled, as shown in Figs. 4 and 5 at D and E, respectively. The strips are then placed side by side, and the ends of the several projections B are glued or otherwise secured together. The open-work panel thus produced is shown in Fig. 6, the curved V-shaped indentations a corresponding to form the openings.

I do not claim herein the process of making 60 ornamental surfaces by first cross-cutting the wood, then splitting the same, and finally securing the strips together so as to reform the surface; nor do I claim the method of ornamenting wood by a design produced by cross- 65 cutting; nor the particular design here shown by an ornamental open-work panel. All these inventions are the subject-matter of separate applications filed or to be filed by me.

I do not limit my claim to the combination 70 of all the steps above mentioned, since, for instance, the third step may be omitted, and the strips shown in Figs. 2 and 3 may be formed into a panel by uniting their edges without further ornamentation, the result in such case 75 being an open-work panel having a flat or plane surface. The panel thus formed may then be ornamented in any desired manner— as, for instance, by cutting beveled channels 80 C, Fig. 7, longitudinally with the grain and along the lines of junction of the strips and by cutting similar channels, F, transversely across the surface. I do not, therefore, limit the invention to the application of any particular amount of ornament to the panel formed 85 by my process.

I claim as my invention—

1. The hereinbefore-described process of making ornamental open-work panels, which consists in, first, producing upon the material 90 a series of alternating channels and ridges transverse to the grain; second, dividing said material into strips at right angles to the direction of said channels; and, third, securing the said strips together with their channeled 95 and ridged edges in juxtaposition, substantially as described.

2. The hereinbefore-described process of

making ornamental open-work panels, which consists in, first, producing upon the material a series of alternating channels and ridges transverse to the grain; second, dividing said material into strips at right angles to the direction of said channels; third, molding or ornamenting the front face or faces of said strips;

and, fourth, securing said strips together with their channeled and ridged edges in juxtaposition, substantially as described.

FREDERICK MANKEY.
